(57) **CLAIM**

The ornamental design for a “sling,” as shown and described.

DESCRIPTION

FIG. 1 is a front perspective view of a sling;

FIG. 2 is a front view of a sling;

FIG. 3 is a back view of a sling;

FIG. 4 is a top view of a sling;

FIG. 5 is a bottom view of a sling;

FIG. 6 is a right side view of a sling; the left side view being a mirror image thereof;

FIG. 7 is a front perspective view of a second embodiment of a sling;

FIG. 8 is a front view of a second embodiment of a sling;

FIG. 9 is a back view of a second embodiment of a sling;

FIG. 10 is a top view of a second embodiment of a sling;

FIG. 11 is a bottom view of a second embodiment of a sling;

FIG. 12 is a right side view of a second embodiment of a sling, the left side view being a mirror image thereof;

FIG. 13 is a front perspective view of a third embodiment of a sling;

FIG. 14 is a front view of a third embodiment of a sling;

FIG. 15 is a back view of a third embodiment of a sling;

FIG. 16 is a top view of a third embodiment of a sling;

FIG. 17 is a right side view of a third embodiment of a sling;

FIG. 18 is a right side view of a third embodiment of a sling, the left side view being a mirror image thereof;

FIG. 19 is a front perspective view of a fourth embodiment of a sling;

FIG. 20 is a front view of a fourth embodiment of a sling;

FIG. 21 is a back view of a fourth embodiment of a sling;

FIG. 22 is a top view of a fourth embodiment of a sling;

FIG. 23 is a bottom view of a fourth embodiment of a sling;

FIG. 24 is a right side view of a fourth embodiment of a sling, the left side view being a mirror image thereof;

FIG. 25 is a front perspective view of a fifth embodiment of a sling;

FIG. 26 is a front view of a fifth embodiment of a sling; the back view being FIG. 3; the side view being FIG. 41, the left side view being a mirror image thereof;

FIG. 27 is a top view of a fifth embodiment of a sling;

FIG. 28 is a bottom view of a fifth embodiment of a sling; FIG. 29 is a front perspective view of a sixth embodiment of a sling; FIG. 30 is a front view of a sixth embodiment of a sling; the back view being FIG. 9; the side view being FIG. 42, the left side view being a mirror image thereof; FIG. 31 is a top view of a sixth embodiment of a sling; FIG. 32 is a bottom view of a sixth embodiment of a sling; FIG. 33 is a front perspective view of a seventh embodiment of a sling; FIG. 34 is a front view of a seventh embodiment of a sling; the back view being FIG. 15; the side view being FIG. 43, the left side view being a mirror image thereof; FIG. 35 is a top view of a seventh embodiment of a sling; FIG. 36 is a bottom view of a seventh embodiment of a sling;

FIG. 37 is a front perspective view of an eighth embodiment of a sling; FIG. 38 is a front view of an eighth embodiment of a sling; the back view being FIG. 21; the side view being FIG. 44, the left side view being a mirror image thereof; FIG. 39 is a top view of an eighth embodiment of a sling; FIG. 40 is a bottom view of an eighth embodiment of a sling. FIG. 41 is a side view of the fifth embodiment; FIG. 42 is a side view of the sixth embodiment; FIG. 43 is a side view of the seventh embodiment; and, FIG. 44 is a side view of the eighth embodiment. The broken lines in the drawings are for illustrative purposes only and form no part of the claimed design.
